Primary Examiner — Bridget L Eland*(74) Attorney, Agent, or Firm* — Fulbright & Jaworski LLP(57) **CLAIM**

The ornamental design for an insertion device, as shown and described.

DESCRIPTION

FIG. 1 is a front perspective view of an insertion device showing our design;

FIG. 2 is a back perspective view thereof;

FIG. 3 is a back view thereof;

FIG. 4 is a front view thereof;

FIG. 5 is a left side view thereof;

FIG. 6 is a top view thereof; and,

FIG. 7 is a bottom view thereof.

The dashed lines in FIGS. 1-7 represent environmental structure and form no part of the claimed design.
